BEVERAGE COOLING CONTAINER

William T. Skrzynski, Detroit, Mich.

Application December 2, 1949, Serial No. 130,745

1 Claim. (Cl. 257—14)

1

The present invention relates to a beverage container, and in particular to improved means for cooling the contents of a conventional dispensing container such as a beer barrel or the like.

Prior to the present invention, it has been common to cool a beverage, such as beer for example, within its container by circulating a coolant fluid through coils inserted within the container. Cleaning and recoating of the interior of the container, as must frequently be done, particularly with beer containers and the like, is rendered difficult when internal coils are used, and such internal coils frequently harbor bacteria and other organisms which render them unsanitary. Such cooling means also tend to cool the entire contents of the container. Accordingly, they are unsatisfactory for use with metal containers, such as conventional steel, aluminum, or stainless steel beer barrels or kegs since there is a heat transfer from the atmosphere through the entire sidewall areas of such barrels or kegs, and the time required to chill the beverage is materially increased due to the large volume of beverage which is being cooled and which is surrounded by thermal conductive material. Also objectionable sweating occurs in such installations due to moisture condensation on the cold sides of the metal container.

Further, in such internal cooling coil constructions, both installation and operating costs of the refrigerating system for the fluid coolant are appreciably increased as a consequence of the cooling of the entire contents of the metal container and the excessive heat transfer through the sidewalls thereof. Insulation of such containers has been attempted but this adds to the cost of the container and greatly increases its bulk.

Some prior constructions have embodied a coolant inlet port located near the top of a barrel and a coolant outlet port located near the bottom of the barrel. This is a decided disadvantage since the port at the bottom must be plugged or closed to prevent loss of coolant when the barrel is not connected to the cooling system. In addition, when disconnecting a barrel involving such a construction from a source of coolant supply, the coolant then in the barrel will spill from the outlet port until it is plugged. The present invention has solved this problem by a novel construction wherein both ports are on the same horizontal level above the cooling chamber.

A primary object of the present invention is to provide an improved, efficient beverage cooling and dispensing container adapted to utilize a

2

conventional tap rod, which will stratify the cooled beverage near the bottom of the container and adjacent the end of the tap rod, without cooling the entire beverage contents to the dispensing temperature, and which will, therefore, minimize cooling of the entire barrel and the resultant sweating of the side walls of such metal containers.

Another object of the present invention is to provide an improved and highly efficient cooling means for beverage containers, which is particularly adapted for use with beverage dispensing barrels, which is economically installed either on existing barrels or as an integral feature of new barrels, and which does not interfere with such cleaning, sterilizing, and recoating of the interior of the container as may be required.

Another object of the present invention is to provide a cooling means for beverage containers, which includes a cooling chamber, and inlet and outlet ports in communication with said cooling chamber and adapted to be connected in a circuit of circulating fluid coolant, the said ports being so located that the source of circulating coolant 20 may be detached from the outlet port without spilling coolant from the chamber and the cooling chamber can stand unplugged without leaking coolant therefrom when it is filled with coolant.

Another object of the present invention is to provide a sturdy beverage container having a cooling chamber affixed to the exterior thereof which will withstand rough handling, and wherein the cooling chamber is well braced and strengthened to prevent buckling or denting of the cooling chamber during handling of the container.

It is another object of the present invention to provide a cooling means for beverage containers, particularly beverage dispensing barrels, which is simple in construction, which provides an efficient circulation of coolant so as to quickly cool the desired portion of the beverage, and which is simple and sturdy in construction, thus being easily adapted for manufacture by mass production methods at low cost.

Other objects of this invention will appear in the following description and appended claim, reference being had to the accompanying drawings forming a part of this specification wherein like reference characters designate corresponding parts in the several views.

A practical embodiment of the present invention comprises a barrel-like container having an outside bung plate attached thereto and a draft

attachment disposed on the top thereof. A shell is disposed around the lower sidewalls of the container and spaced therefrom to form a cooling chamber. Baffle plates are disposed within the cooling chamber between the container sidewall and the shell to efficiently guide the flow of a coolant throughout the cooling chamber. Inlet and outlet ports are located in the bung plate above the cooling chamber and communicate with the cooling chamber on different sides of a separator plate which is disposed within and obstructs the cooling chamber. The inlet and outlet ports are adapted for connection in a circuit with a source of circulating fluid coolant, preferably water.

In the drawings:

Fig. 1 is a side elevation of a beverage container embodying the present invention, with portions broken away to reveal the internal construction.

Fig. 2 is an outside elevation of the bung plate taken along the line 2—2 in the direction of the arrows, Fig. 1.

Fig. 3 is a bottom plan view of the container shown in Fig. 1.

Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

A preferred embodiment of the present invention is shown in the drawings and comprises the all-metal welded barrel 10 having an outside type bung plate 11 disposed on the sidewall thereof and extending outwardly therefrom, and a tap seal 12 adapted to accommodate a conventional draft attachment or tap rod assembly (not shown). The bung plate 11 is provided with the tapered opening 13 which mates with the opening 14 in the sidewall of the barrel 10 and communicates with the interior to allow filling of the said barrel 10. Two substantially vertical conduits 15 and 16 are disposed in the bottom portion of the bung plate 11. The said conduits 15 and 16 terminate in ports 15a and 16a near the bung opening 13 at one end and terminate in openings 15b and 16b at the bottom of the bung plate 11 at the other end. Any suitable type of fluidtight connection may be provided between the ports 15a and 16a and the line (not shown) for supplying or carrying away the fluid coolant.

The barrel 10 is provided near its bottom with spaced substantially vertical baffles 17 which are welded to the sidewall of the barrel 10. The baffles 17 are so located that they are in two horizontal levels, alternate baffles being in the same horizontal level. The barrel 10 is provided with the usual circumferential bumpers 18 which protect the barrel and facilitate rolling thereof. An annular shell 19 is tightly fitted over the lower end of the barrel and over the baffles 17. The top edge of the shell 19 is welded to the bottom portion of the lower bumper 18, and the bottom edge of the shell 19 is welded to the sidewall of the barrel 10 to provide a fluid-tight seal and form the cooling chamber 20 which extends over the lower portion of the barrel only. Thus, it will be seen that when the shell 19 is secured in place, the chamber 20 is provided with a series of baffles 17 which are alternately open at the top and bottom to direct the flow of circulating

coolant fluid up and down along the path indicated by the arrows in Fig. 1. Eight of such baffles 17 have been found satisfactory, but any suitable number may be used.

5 A separator plate 21 is welded to the sidewall of the barrel 10 at the same time the baffles 17 are welded in place. The separator plate 21 is so formed as to completely obstruct the cooling chamber 20, and is located in the cooling chamber 20 below the bung plate 11 in a vertical plane which extends between the conduits 15 and 16 in the bung plate 11. Thus, when a circulating coolant is led in through one of the ports 15a or 16a, it must necessarily pass out through the other of the said ports.

10 The container of the present invention is installed and operated as follows:

15 The port 15a, for example, may be considered the inlet port. A source of circulating coolant fluid (not shown) is attached to the inlet port 15a. The port 16a, which then becomes the outlet port, is connected to a drain or coolant supply tank. The coolant is circulated along the up and down path indicated by the arrows in Fig. 1 and effectively cools the beverage in the lower portion of the container, finally contacting the separator plate 21 and passing out the outlet port 16a.

20 Shut off valves, not shown, may be provided, if desired, within the ports 15a and 16a so as to prevent coolant fluid within the cooling chamber 20 from escaping when ports 15a and 16a are not connected with the cooling system, as for example when the barrel is in transport from the brewery or held in reserve as a stand-by. However, due to the construction of the present invention wherein the ports are located on a horizontal level above the cooling chamber, such valves are not necessary and any conventional means such as rubber stoppers, for example, can be used to close the ports.

25 Inasmuch as beverages such as beer having high water content are poor thermal conductors, a relatively shallow layer of the beverage is quickly chilled to the dispensing temperature and stratified at the bottom of the barrel 10. By virtue of cooling from below, convection currents are avoided in the beverage. Consequently the beverage temperature rapidly drops near the bottom of the barrel 10, while the temperature of the major portion of the beverage above the lower chilled layer remains higher. Thus, sweating of the sidewalls is substantially avoided except at a relatively small lower portion thereof. Furthermore, inasmuch as the main body of the beverage is warmer than the chilled bottom layer thereof, the transfer of heat thereto is reduced to a minimum, with a consequent reduction of the operating cost of the refrigerating equipment for the fluid coolant.

30 A particular advantage of the cooling means of the present invention is that it may be readily and economically installed as an addition to existing containers of the type shown, which provide the bumpers 18. Installation merely requires forming of the conduits 15 and 16 in the bung plate 11. The baffles 17 and the separator plate 21 are then affixed to the side of the barrel 10, and the shell 19 is secured at its upper edge against the lower bumper 18 and at the bottom edge against the sidewall of the barrel 10.

35 The baffles 17 and separator plate 21 provide additional strength for the cooling chamber and minimize the danger of damage to, or buckling 40 of the chamber.

From the foregoing, it will be seen that I have provided an improved, efficient, simple, and economically constructed beverage container and cooling means. The construction affords cooling of a layer of beverage near the bottom of the container without cooling the entire beverage supply. Thus, beverage near the bottom of the container from which it is drawn may be rapidly cooled at a minimum time and operating cost. In addition, sweating of the sidewalls of a metal container embodying the present invention is substantially eliminated without the additional expense of insulation.

Having thus described my invention, I claim:

In a metal beverage container and dispenser adapted to be cooled by a circulating fluid coolant, the combination of a cooling chamber along the lower sidewall thereof, the lower sidewall of the container comprising the inner wall of said cooling chamber, and the outer wall of said cooling chamber consisting of a shell surrounding and spaced from the lower sidewall of the container and having its top and bottom edges secured to said container in a fluidtight seal; a plurality of spaced substantially vertical baffle members extending between the inner wall of said cooling chamber and the outer wall thereof, said baffle members defining a vertical sinuous

path for the flow of fluid therethrough between the top and bottom portions of said cooling chamber; a separator plate which obstructs said cooling chamber and prevents passage of the coolant fluid therebeyond; a bung plate disposed on the side of said container above said cooling chamber and having inlet and outlet conduits therein communicating with said cooling chamber on different sides of said separator plate.
